UNITED STATES PATENT OFFICE.

RICHARD D. YOST, OF GLENCOE, MARYLAND.

SIEVE-OPERATING DEVICE.

SPECIFICATION forming part of Letters Patent No. 314,904, dated March 31, 1885.

Application filed December 17, 1884. (No model.)

To all whom it may concern:

Be it known that I, RICHARD D. YOST, a citizen of the United States, residing at Glen-
5 coe, in the county of Baltimore and State of Maryland, have invented certain new and use-
ful Improvements in Sieve-Operating Devices, of which the following is a specification.

My invention relates to a device for oper-
10 ating an ordinary hand-sieve, such as is used
for household and other purposes. The ob-
ject is to provide a convenient device which
will support the sieve and enable the desired
shaking motion to be given it, thus obviating
15 the necessity of taking the sieve, as usual, in
the hand.

In the accompanying drawings, Figure 1 is
a side view of a table-top to which the im-
proved device is attached, supporting the
sieve above the table-top. Fig. 2 is a top or
20 plan view of the same. Fig. 3 is a view of
the device, excepting the clamp by which it
is attached to the table-top. Fig. 4 is a view
of the cross-bar which supports the sieve.
Fig. 5 is a view of the clamp and part of the
25 device.

The letter A designates the top of a table;
B, an ordinary dough-mixing board, such as is
commonly used by pastry-cooks. The sieve
30 C is supported by an arm, D, above the mix-
ing-board. This arm has two shoulders, a,
and carries a cross-bar, b, provided at its ends
with similar shoulders, a', and at its center
35 with a notch, c, which sets astride of the arm
and meshes with a similar notch thereon. By
this construction the cross-bar and arm are
halved together, and all the shoulders a and
a' are equidistant from the point where the
two are halved.

Any suitable means may be used to secure
40 the cross-bar. In the present instance a wire,
d, bent in the form of a ring, passes through
both cross-bar and arm and fastens the two
securely.

The cross-bar and arm having the shoulders
45 a and a' equidistant from the attaching-point
constitute a seat for the sieve C. Sieves of
various sizes may set on this seat. The arm
is supported by its end e being attached in
any suitable manner to a pivoted hub, F.
50 This hub has a round bore, which is occupied
by a fixed upright stud or shaft, G. A set-

screw, h, entering the side of the hub, impinges
against the stud, and serves to make the hub
rigid with respect thereto. The lower end of
the stud is attached to a clamp-plate, I, and
55 made fast thereto, and the clamp-plate has
two jaws, k, one of which takes over and the
other under the table-top B. A set-screw,
n, in one of the jaws serves to make the clamp-
plate fast to the table-top. A spiral spring,
60 p, surrounds the stud G, and its lower end
rests on top of the clamp-plate, while its up-
per end bears up against the hub F. This
spiral spring serves to temporarily support
65 the hub, arm, and sieve when the set-screw h
is loosened, and if it is desired to raise or
lower the arm and sieve, as indicated by broken
lines in Fig. 1, the spiral spring will react or
yield for that purpose. As the hub is pivoted
70 on the stud, the sieve-supporting arm D may
turn around the stud for an axis in a hori-
zontal plane. By loosening the set-screw h
the arm may be moved to one side so as to
change the position of the sieve, as indicated
75 by broken lines in Fig. 2. By the arm or its
hub being loosely attached on the upright stud
G, and made fast thereto by the set-screw h,
the sieve may be turned either in a horizontal
80 plane or adjusted vertically.

In constructing the arm provision is made
so that it will spring or yield laterally. To
this end the arm at a point between the sieve
and hub is made thin, as at q. By having this
“spring” feature in the arm while its sup-
85 ported end is rigid, the sieve may be vibrated
in a horizontal plane. The desired “shaking
motion” therefore may be given the sieve
while it is supported on the arm. The sieve, be-
ing supported above the dough-mixing board
90 and containing flour, may be operated by strik-
ing it at the side with the hand, which will
cause it to vibrate or shake.

It is obvious that certain features of the in-
vention may vary from the construction here
shown without impairing the operativeness of
the others.

Having described my invention, I claim and
desire to secure by Letters Patent of the United
States—

1. In a sieve-operating device, the combina-
tion of a suitable support with an arm having
a portion of its length made thin, so as to spring

or vibrate in a horizontal plane, and provided at one end with a seat for a sieve, as set forth.

2. In a sieve-operating device, the combination, with an upright stud, of an arm having a portion of its length made thin, so as to spring or vibrate in a horizontal plane, provided at one end with a seat for a sieve, and loosely attached at its other end to said upright stud, and means for making it rigid therewith, whereby it may be turned in a horizontal plane or adjusted vertically, as set forth.

3. The combination, in a sieve-operating

device, of an upright stud, an arm provided at one end with a seat for a sieve, and having its other end loosely attached to the upright stud, means for making the arm rigid on the stud, and a spring, *p*, about the stud bearing up against the arm, as set forth.

In testimony whereof I affix my signature in presence of two witnesses.

RICHARD D. YOST.
